REMOVABLE CAPILLARY TUBE UNIT

George O. R. Lindgren, Willoughby, Ohio, assignor
to The Weatherhead Company, Cleveland, Ohio,
a corporation of Ohio

Application October 2, 1945, Serial No. 619,733

6 Claims. (Cl. 62—127)

1

My invention relates to elements for fluid conveying systems, especially for refrigerating systems.

The principal object of this invention is to facilitate the removal and replacement of the expansion element of a refrigerating system, such as a capillary tube expansion element, while maintaining a tight, leak-proof connection of the expansion element with the connecting portions of the refrigerating system in use.

Other objects are to avoid defrosting the evaporator by the admission of warm liquid into the evaporator through the capillary tube in the period between cycles of operation of the compressor, to increase the capacity of the evaporator, by bringing the returning gas or semi-liquid from the evaporator into heat exchanging relation with the capillary tube, or with the liquid entering the capillary tube, or both.

Another object of this invention is to provide an adjustment for the restriction through a capillary tube expansion element whereby a single unit may be used with evaporators working at various different capacities.

Other objects, features and advantages of the invention will be apparent from the following description of preferred embodiments thereof.

In the accompanying drawings:

Fig. 1 is a longitudinal section through a casing and removable capillary tube cartridge constructed according to this invention;

Fig. 2 is a similar view with parts in elevation showing the cartridge partly removed from the casing;

Fig. 3 is a longitudinal section similar to Fig. 1 showing a capillary tube cartridge with provision for adjustment of the length of the capillary tube;

Fig. 4 is a front elevation of the assembly partly in section on the line 4—4 of Fig. 3;

Fig. 5 is a vertical section of the shell only taken on the line 5—5 of Fig. 3;

Fig. 6 is an end view of the inner end of the capillary tube unit; and

Fig. 7 is a vertical transverse section of the tube unit taken on line 7—7 of Fig. 3.

Like reference characters are utilized throughout the drawing to designate like parts.

The improved capillary tubing expansion unit is essentially formed as a removable unit within a fixed casing which is preferably a permanent part of the refrigerating mechanism when used in connection with such mechanism. This unit is interposed in the stream of refrigerating fluid which incidentally is filtered before it is received by the capillary tube. After passing through the

2

capillary tube or merely a section thereof, the fluid is then delivered in regulated quantities to the evaporator.

The simplest form of the invention illustrated in Figs. 1 and 2 comprises a casing 11 adapted to be connected as a permanent part of a fluid conveying system such as a refrigerating system and having a boss 12 adapted to be connected in fluid-tight relation with the tube leading from the condenser and a boss 13 adapted to be similarly coupled to the tube leading to the evaporator of the refrigerating system. The removable cartridge includes a spool 14 having end plates 15 and 16 about which is wound a capillary tube 17. One end of the tube is open, as indicated at 18, and the other is sealed into a radial opening 19 in the spool 14 leading into an axial recess 20.

The spool 14 and end plates 15 and 16 are fastened together in gas-tight relation, either by being formed integral with each other or by being welded or brazed together as indicated in the drawings. The end plate 15 is provided with a sealing gasket 21 adapted to seal against a raised seat 22 formed on the end wall of the casing 11 and surrounding a bore 23 which communicates with the bore of the fitting boss 13. A cylindrical filtering screen 24 is connected to the end plates 15 and 16 and surrounds the capillary tube 17. The end plate 16 is provided with a flange 25 fitting within and flush with the open end of the casing 11, and a cap 26 carrying a sealing gasket 27 is arranged to be screwed on the open end of the casing 11 so as to force the gasket 27 into sealing relation with the flange 25 and the end of the casing, and simultaneously to force the gasket 21 into sealing relation with the seat 22.

In assembled condition liquid from the condenser or compressor enters the casing 11 through the fitting boss 12, passes through the screen 24 and fills the spaces between the convolutions of the capillary tube 17 around the spool 14. This fluid enters the open end of the capillary tube 18 and after passing therethrough is admitted through the recess 20 and the bore 23 to the tube leading to the evaporator connected to the fitting boss 13. Thus in assembled position the capillary tubing 17 is installed by leak-proof connections as a permanent part of the refrigerating system in the usual position between the compressor and the evaporator.

One of the service problems encountered with capillary tube expansion elements in refrigerating systems is that the opening in the tube tends to become restricted so that the tube becomes sluggish and must be replaced. In accordance

with the present invention the tube is readily replaced by first relieving the pressure in the system and removing the screw cap 26 from the casing 11. The capillary tube cartridge can then be slipped out of the casing 11 as a unit, as illustrated in Fig. 2, and be replaced with a new cartridge which has been maintained in dehydrated condition so as to restore the system to its original efficiency very quickly thereby saving time and excessive cost of repair.

It is frequently desirable to adapt the removable capillary tube unit for use under varying conditions of load by utilizing a part only of its effective length. This may be accomplished by tapping the capillary tube as illustrated in Figs. 3 to 7 inclusive.

In this form of the invention the shell 28 has its inner end formed with a fitting boss 36, which is internally screw threaded for connection with the piping or other fitting leading to the evaporator proper. The inner end of the casing 28 has a port 37 surrounded by a raised seat 38. In the illustrated embodiment, two similar raised seats 38a which have no ports are formed on the inner end of the casing spaced 120 degrees on each side of the seat 38. The lower fitting boss 39 is also internally screw threaded for connection to the piping from the compressor or condenser and serves as an inlet for the refrigerating fluid.

A cap 41 is screw threaded over the open or outer end of the casing 28. This cap has an annular groove created by the presence of a central boss 42. This annular groove holds a circular gasket 43 by which the open end of the casing is sealed.

The capillary tubing may be carried on a spool 44 shown with a solid core which terminates at its inner end in a plate 45. The plate 45 has a spider 46 formed with radiating arms, in the present instance illustrated as three in number. The three arms of the spider have intermediate outlet openings or ports 47, 48 and 49. These openings pass through the inner end plate as shown in Fig. 3 and each is adapted to connect with the outlet port 37 of the casing. Each outlet opening is surrounded by a gas-tight gasket 50 adapted to seal against the seat 38 to connect the opening with the outlet port 37, or to seal against one of the seats 38a to close the opening. The intermediate outlet ports 47, 48 and 49 connect with radial bores 51 which are sealed at the ends of the spider arms by plugs 52. Each bore receives one or more ends of the capillary tubing.

On the end plate 45 of the spool diametrically opposite one opening or outlet there is firmly fixed a projecting pin 53 by which the spool may be selectively located against the inner end of the casing and with one of the outlet openings in registry with the port 37.

The opposite end 54 of the core carries a flanged plate 55. This fits the inner end of the casing closely and serves to center the spool in the casing. It will also be noted that the end of the flange plate fits against the gasket 43 thus sealing the space around the central portion of the spool.

The capillary tubing consists of a plurality of separate lengths of tubing which have been indicated as three in number and marked 57, 58 and 59. The inner tube 59 has one of its ends sealed into one arm of the spider 46 and communicating with the port 47, and its other end connected to another arm of the spider and communicating with the port 48. The doubled tube

59 is then wound spirally about the core 54. The intermediate length of tube 58 has one of its ends connected to the spider to communicate with the port 48 and the other of its ends connected to 5 communicate with the port 49. The doubled tube 58 is then wound spirally about the core 54 in the opposite direction to the winding of the tube 59, forming an intermediate layer of tubing. The outer tube 57 has one end connected into the bore 10 51 which communicates with the port 49 and is wound singly about the core 54, forming the outer 20 layer of tubing. The other end 60 of the tube 57 is left open and disposed adjacent the left hand end of the core 54, as shown in Fig. 3. A screen 61 surrounds the capillary tubing, as shown in Fig. 3, and serves to filter the liquid entering the casing 28.

Either one of the ports 47, 48 or 49 may be placed in communication with the outlet port 37 by selecting one of the three different positions of the cartridge. Registration of the ports is assured by providing the end wall of the casing 28 with three holes 62, 63 and 64 into any one of which the pin 53 carried by the spool end 45 may be inserted.

When the pin 53 is placed in the hole 62, in the position shown in Fig. 3, the port 47 is aligned with the outlet port 37 and the ports 48 and 49 are closed by the seats 38a. Thus liquid which 30 enters the casing through the fitting boss 39 may pass through the screen 61 and into the open end 60 of the tube 57. After passing through the length of the capillary tube 57 the liquid passes the blocked port 49 and enters one end of the intermediate tubing 58. From the tubing 58 the liquid passes the blocked port 48 and enters one end of the inner layer of tubing 59. From the other end of the tubing 59 the liquid passes through the port 47, the outlet port 37 and the outlet boss 36 into the pipe leading to the evaporator. In this position the liquid is compelled to pass through all three lengths of tubing 57, 58 and 59, thus providing the greatest restriction for the smallest sized 45 evaporator or the lightest loads. By turning the cartridge counterclockwise through 120° the pin 53 may be entered in the hole 63. In this position the port 48 is aligned with the outlet port 37 and the ports 47 and 49 are closed. In this position the liquid enters the outer tube 57, passes the blocked port 49 and enters the intermediate tube 58 and from the opposite end of the tube 58 passes through the port 48 and thence to the outlet port 37. Thus the liquid must pass through 55 two lengths of the capillary tubing 57 and 58 so that a medium restriction is provided for a medium load or medium sized evaporator. By turning the spool counterclockwise through another 120° the port 49 is aligned with the outlet port 37 and the ports 47 and 48 are closed. The liquid can no longer escape through the port 48 and thus enters one end of the capillary tubing 59 then passes through the port 49 through the outlet port 37. In this position the minimum restriction is provided for the heaviest 60 loads or the larger evaporators.

With this arrangement it will be apparent that the amount of restriction in a given installation may be adjusted and also that a single standard cartridge may be manufactured for installation in refrigerating systems having evaporators of different capacities. Thus in the illustrated embodiment refrigerators might be made with three different sized evaporators and the single cartridge illustrated could be used in service to re-

place the capillary tube unit of any one of the three different sizes.

Various modifications and revisions of the described embodiment of the invention may be adopted without departing from the scope of the invention as defined in the following claims.

I claim:

1. In combination, a casing having an open end, a closure for said end, inlet means for introducing a refrigerating fluid into said casing, an outlet eccentrically positioned in the opposite end, a spool insertable into the casing through the open end, a number of capillary tubes coiled on said spool, a spool-end having an equal number of intermediate outlet ports, means for selectively connecting one of said ports to said outlet, one of said tubes being connected to one of said ports, and each of the other tubes connecting successive ports.

2. In combination, a casing having an open end, a closure for said end, inlet means for introducing a refrigerating fluid into said casing, an outlet eccentrically positioned in the opposite end, sealing means equally spaced with said outlet circumferentially of the end, a spool insertable into the casing through the open end, a number of capillary tubes coiled on said spool, a spool-end having an equal number of intermediate outlet ports, means for selectively connecting one of said ports to said outlet, one of said tubes being connected to one of said ports, and each of the other tubes connecting successive ports, the ports not being connected to said outlet being sealed by said sealing means.

3. In combination, a casing having an open end, a closure for said end, inlet means for introducing an expansible fluid into said casing, an outlet for said fluid from the opposite end of the casing, a spool insertable into the casing through the open end, a number of capillary tubes coiled on said spool, a spool end having an equal number of intermediate outlet ports connected in series with said coils for delivering from one or more of them, and means for selectively connecting one of said outlet ports to the outlet in the end of the casing.

4. A capillary tube unit for a refrigeration system comprising a casing having inlet and outlet ports, a plurality of lengths of capillary tubing disposed in said casing, a member in said casing having a plurality of intermediate outlet ports equal in number to the number of tube lengths, said lengths of tubing being connected in series by means of said member in the casing having a plurality of intermediate outlet ports with the first length having one end open to the casing inlet port and with the last length having its outlet end connected to the last of said intermediate outlet ports, said casing having means for sealing off all of said intermediate ports except

one which is in communication with said casing outlet port, said member being selectively positionable in said casing with any one of said intermediate outlet ports in communication with said casing outlet port.

5. A capillary tube unit for a refrigerator comprising a generally cylindrical casing having a closed end wall, said casing having a generally cylindrical chamber with portions of reduced section at each end thereof, an inlet port in the side wall of said casing and an outlet port in the end wall thereof, a spool in said casing having end flanges fitting within said reduced bore sections, an outlet port in one of said end flanges aligned and sealed with said casing outlet port, a capillary tube coiled on said spool having one end open to said chamber and the other end connected to said flange outlet port, a filter screen surrounding said coiled tubing and attached at its ends to said spool flanges, said screen being spaced from the side wall of said cylindrical chamber intermediate its reduced sections whereby incoming fluid may pass through substantially the entire surface of said screen and bathe said coiled tubing, and a closure member for said casing that urges said spool toward said casing end wall.

6. A capillary tube unit for a refrigerator comprising a generally cylindrical casing having a closed end wall, said casing having a generally cylindrical chamber, an inlet port in the side wall of said casing and an outlet port in the end wall thereof, a spool in said casing having end flanges, an outlet port in one of said end flanges aligned and sealed with said casing outlet port, a capillary tube coiled on said spool having one end open to said chamber and the other end connected to said flange outlet port, a filter screen surrounding said coiled tubing and attached at its ends to said spool flanges, cooperating means disposed on said spool flanges and at each end of said chamber and centering said spool in the chamber, said screen being spaced from the side wall of said cylindrical chamber intermediate its ends whereby incoming fluid may pass across substantially the entire surface of said screen and through the latter and bathe said coiled tubing, and a closure member for said casing that urges said spool toward said casing end wall.
